RAIL CUSHION

Thomas B. Upchurch, Jr., Raeford, N. C.

Application September 1, 1939, Serial No. 293,065

1 Claim. (Cl. 238—283)

This invention relates to a rail cushion for rail roads and more especially to a tie plate having certain resilient and shock absorbing qualities. It is a well known fact that the conventional metallic tie plate which is now in use has a tendency to dig or mash into the top of the cross tie when the rolling stock passes over the rails, thereby damaging the tie. This digging effect is partially noticeable near the edges of the tie plates because the edges are usually sharp and have a tendency to cut the wood fibers. Also the metallic plates do not absorb the shock; consequently, there is a tendency for the spikes, which secure the rails upon the plate and cross-tie to loosen from time to time, necessitating frequent redriving.

It is therefore an object of this invention to provide a tie plate made of some resilient and fibrous material such as rubber and cotton fiber or the like, which may be used between the cross tie and the rail. A suitable rubber composition impregnated into the fabric may be used in order to preserve the same and to give the tie plate a longer life.

It is another object of this invention to provide the combination of a spike, a rail, and a cross tie with a resilient plate so positioned that it will serve as a lock washer for the spike as well as a cushion for the rail. This locking feature comprises the upwardly and inwardly turned side edges which encircle the lower flanges of the rail and are disposed directly beneath the heads of the spikes. In other words, the folded edges of the tie plate fit beneath the heads of the spike very much in the same manner that a lock washer fits beneath the nut of a bolt. When in an installed position, the tie plate is wrapped around the lower flanges of the rail, and the portion of the tie plate which is clamped upon the upper side of the flange by the spike head also acts to cushion any shock upon the spike. This lock washer effect serves to keep the spike from working loose and lessens the danger of derailment, which is very often caused by loosened spikes.

It is a further object of this invention to provide a resilient tie plate which is adapted to work beneath the lower flanges of a rail, said tie plate having in-turned ribbed or beaded edges which encircle the lower flanges and are normally disposed above the upper flange of the rail and upon the spike heads.

Some of the objects of the invention having been stated, other objects will appear as the description proceeds, when taken in connection with the accompanying drawing, in which—

Figure 1 is a plan view of a portion of a railroad showing my improved tie plate associated therewith;

Figure 2 is an enlarged vertical sectional view taken along the line 2—2 in Figure 1;

Figure 3 is an isometric view of the tie plate shown in the preceding figures before the same has been installed;

Figure 4 is an enlarged sectional view similar to Figure 2, showing a slightly modified form of the tie plate in an installed position;

Figure 5 is an isometric view of the tie plate shown in Figure 4.

Referring more specifically to the drawing, the numeral 10 denotes suitable cross ties upon which 15 my improved tie plates 11 are adapted to rest. These tie plates have rails 14 resting thereupon, said rails being secured upon the tie plates 11 and to the cross ties 10 by any suitable means such as spikes 15. It is preferable to incorporate 20 in the tie plates 11, a plurality of layers of fibrous material 16 such as cotton fabric, or the like. This fabric 16 is usually impregnated with a suitable binder such as rubber or the like, and upon each side of the fabric 16 a surface of rubber 17 25 is provided. The fabric and rubber are vulcanized together much in the same manner employed in the manufacture of pneumatic tire casings.

Along each edge of the tie plate 11, a ribbed or bead portion 18 is formed which is reinforced 30 by any suitable means such as a metallic cable or rod 19. It will be noted that the ribs 18 are turned inwardly and when in an installed position they are adapted to normally rest upon the heads of the spikes 15. By placing the ribs 18 35 over the heads of the spikes 15 a stabilizing effect is produced. Also by providing this curled inturned rib portion 18 the plate 11 will remain beneath the rail regardless of whether the spikes are driven or not. In other words, should the 40 head of a spike come off, or should a spike become completely removed from the cross tie, these ribs would curl farther inwardly and rest upon the top of the lower flange of the rail 14. It frequently happens that one of the two spikes, 45 which normally hold to tie in place, becomes removed, and when such is the case, if there is not an inturned rim portion such as 18, the tie plate will have a tendency to rotate about the remaining spike and leave the vacant space between 50 the lower portion of the rail and the upper portion of the tie 10. The head portions 18 tend to return to the position shown in Figure 3; therefore, they exert a confining effect on the spikes 15.

In order to insure that the spikes will be held in position, however, relative to the tie plates 11, a suitable projection 15a is provided along one face of the spikes 15. This projection is wedge shaped, having its upper portion extending substantially at right angles to the side of the spike. When the projection has once penetrated the tie plate, the shoulder on the upper side thereof will serve to prevent the spike from becoming disengaged from the plate.

Another advantage of having a tie plate made of resilient cushioning material is that of eliminating the necessity of punching holes for the spike 15. In other words, it gives a railroad construction gang a greater range of choice as to the point where the spikes shall be driven, because the tie plate is made of a material that can be easily penetrated by a spike, without having the tie punched beforehand.

20 Especial attention is called to the fact that the tie plate 11 has upwardly and inwardly curled sides. By providing these inturned, curled sides, the wearing surface between the edges of the lower flange and the top side of the tie plate is increased, thereby distributing the wear over a wider area. The result in so distributing the wear, is a longer life of the tie plate. If these curled portions were not provided the wear of the sharp edges on the lower flange would soon 25 30 cut the upper side of the tie plate rendering it defective. Also by having the lower sides of the tie plate rounded, the cutting effect between the edges of the tie plate and the top side of the cross tie is eliminated.

35 Figures 4 and 5 show a slightly modified form of the invention in which a tie plate 25 is provided, which comprises an outer layer of rubber or the like 26 and an inner layer of rubber or the like 27. Between these layers of rubber are a 40 plurality of layers of fibrous material 28 such as cotton cord, fabric or the like. The construction of the material from which this plate is made is similar to that of the tie plate 11 previously described.

45 The side edges of the tie plate 25 are folded upwardly and inwardly so that the inturned edges will normally rest upon the top of the lower flange of rail 14. By providing these inturned edges, the tie plate is prevented from slipping out from under the rail in case of a loosened or broken spike. 50 The side edges of the tie plate (Figure 5) have a plurality of notches 30 cut therein, of substan-

tially the same width as the body portion of a spike. When the tie plate 25 is placed beneath the rail 14 and upon a cross tie 10, a suitable spike 31 is driven downwardly into the tie, at a point coinciding with the notches 30.

As will be seen in Figure 1, it is customary only to place two spikes at each tie plate, the remaining notches 30 being provided in case additional spikes are necessary. These notches penetrate the folded edges of the tie plates, thereby making it possible for the spikes 31 to come into contact with the edges of the lower flange of the rail 14 as shown in Figure 4. When the spike is driven down, the head of the spike normally rests upon an inturned folded edge of the tie plate, which in turn rests upon the upper side of the lower rail flange. This inturned portion serves as a lock washer to keep the spikes from working loose, thereby helping to lessen the danger of derailment caused by loosened spikes and spreading 20 rails. This will also eliminate the necessity of driving down the spikes so often to retighten them.

My improved tie plate is designed to lessen the possibility of the bolts that penetrate the rail splice bars from becoming loose. Such a structure also lessens the noise at the rail joints when the rolling stock passes thereover by serving as a pad and shock absorber under the rails.

25 In the drawing and specification there has been set forth a preferred embodiment of the invention, and although specific terms have been employed, they are used in a generic and descriptive sense only and not for purposes of limitation, the scope of the invention being set forth in the appended claim.

30 I claim:

In a railroad track having cross ties, rails and spikes driven into the cross ties adjacent the lower side flanges of the rails so that the heads 40 of the spikes press against and overlie the upper surfaces of said rail flanges, a cushioning member, made of layers of rubber and fabric vulcanized together and disposed between the lower surface of the rail and the cross ties, said cushioning member extending substantially laterally of the side edges of the rail and being penetrated by said spikes, said cushioning member having its side edges curved upwardly and then inwardly to overlie the heads of the spikes. 45 50

THOMAS B. UPCHURCH, JR.
